RADIO AERIAL

William Edward Hann, Detroit, Mich.

Application December 30, 1940, Serial No. 372,230

8 Claims. (Cl. 250—33)

This invention relates to extensible and retractable radio aerials particularly suited for motor vehicles and the like.

The main objects of this invention are to provide an antenna which may be extended and retracted by utilizing a source of vacuum from the motor of the vehicle upon which it is mounted; to provide an extensible and retractable antenna in which the actuating member does not affect the capacity of the antenna to accumulate radio energy; to provide an antenna of this character in which all of the sections thereof may be extended by power; to provide a power actuated extensible and retractable radio antenna in which the power actuating unit may be located in various different places, wherever space is available, and may be remotely located with respect to the antenna; to provide a power actuated extensible and retractable antenna which may be mounted on any make and design of automobile body, regardless of side wall spaces adjacent the point of mounting; to provide an antenna in which the power cylinder may be of relatively large diameter and length and yet which may be mounted on any automobile.

Other objects and features of novelty of my invention will be either specifically pointed out or will become apparent when referring, for a better understanding of my invention, to the following description taken in conjunction with the accompanying drawing, wherein:

Figure 1 is a broken sectional view of an automotive vehicle having an antenna and a raising and lowering device for the aerial thereof embodying features of my invention;

Fig. 2 is an enlarged broken sectional view of the structure illustrated in Fig. 1;

Fig. 3 is a view of structure, similar to that illustrated in Fig. 1, showing a modified form thereof; and,

Fig. 4 is a view of structure similar to that illustrated in Fig. 2, showing a further form which my invention may assume.

In Fig. 1, I have illustrated a portion of an automobile body 5 which may be a fender, a side or cowl panel, or the like, and a floor 6, on the former of which an antenna 7 is mounted, while under the floor I have illustrated an operating mechanism 8 for raising the aerial thereof. The antenna is mounted by suitable means herein illustrated as a bracket 9 and an insulating rubber collar 11. The operating mechanism 8 embodies a cylinder which is maintained in position by suitable means, herein illustrated as by straps 12. The operating mechanism is joined by a

flexible tube 13 to the casing of the antenna 7, the flexible tube and the operating mechanism being shielded by the body of the vehicle.

In antennas provided with means for raising the aerial thereof and lowering it within the confines of the body, difficulty has been experienced in view of the capacitance added to the aerial by the helically wound flexible tube projected with the aerial. For this reason, and resulting mechanical difficulties, only one joint of the aerial was projected from the body by the actuating mechanism. The additional capacity provided in the aerial by the projection of the coiled wire thereinto detracted from rather than increased the respective capacity of the radio. When practicing my present invention, I eliminate the use of the helical wire from the aerial portions which extends from the supporting base and employ a metal or a flexible di-electric element as the actuating instrumentality. The helical tube joining the actuating cylinder to the antenna base is insulated from the antenna and the body of the vehicle provides a shield which prevents any change in the capacity of the antenna.

25 Referring to Fig. 2, the operating mechanism 8 embodies a cylinder 14 of a length sufficient to provide movement to a piston 15 to raise all of the jointed sections of the aerial to their full extent. The piston is double acting, embodying a central stem 16 on which a pair of cup washers 17 having their flanges presenting toward the cylinder ends are mounted, on either side of a central spool 18. The assembly is clamped in position by a pair of shouldered washers 19 disposed between a flange 21 on the end of the stem 16 and a pin 22 extending through an aperture in the opposite end thereof.

30 A suitable cap 23, not herein illustrated in detail, is threaded or otherwise secured to the right hand end of the cylinder 14 as viewed in the figure, while a similar cap 24 is threaded in the opposite end and provided with a central aperture 25. A flexible actuating rod 26 has one end projected in an aperture 27 in the stem 16 and secured 35 therein by suitable means, herein illustrated as by a set screw 28. The flexible actuating element 26 is preferably made of an extruded di-electric material which may be sealed in the apertures 25 by a resilient sealing band 29. A hollow slotted 40 extension 31 is provided on the front end of the cap 24 in which the end of a flexible casing 32 is secured. The tubing is formed from a coiled wire, the end of which projects within the end of the extension 31 and is secured therein by a 45 clamping ring 33 which draws the split sides of

the extension 31 together to securely anchor the end of the flexible tubing.

The antenna 7 includes an aerial made up of a central section 34, and an outer cylindrical section 35. A tubular casing 36 of the antenna supports the aerial and, as pointed out hereinabove, is attached to the vehicle body by the bracket 9 and the insulating washer 11. The casing 36 supports a guide bushing 37 at its upper end while the aerial section 35 is provided with an annular bushing 38 which bears on the wall of the casing below the bushing 37. The bushings 37 and 38 provide stability to the aerial. An insulating collar 39 is mounted within the casing 36, at the bottom thereof, having an inwardly extending lip 41 through which the flexible rod 26 extends and against which the end of the aerial section 34 abuts when lowered. The end of the flexible tube 32 projects within the insulating collar 39 and is secured in position by a band 42 which clamps about the end of the casing 36. The casing 36 and collar 39 are split so as to be drawn tightly about the upper end of the flexible tube 32.

A stem 44 is threaded into the end of the flexible element 26, the opposite end being threaded in the end of the aerial section 34 and retained in position by a lock washer 45. It will be noted that the operating device 8 and the flexible tube 32 are entirely insulated from the aerial at all times so that its capacity is not changed when the aerial is extended. At each end of the cylinder 14, pipe connections 46 are mounted to which a rubber hose or other conductor is connected. A valve (not shown) controls the application of pressure to one or the other ends of the cylinder, by direct application of pressure or by the use of a vacuum. With the piston at the right hand end of the cylinder, as illustrated in Fig. 1, vacuum is applied through the front pipe connection 46 and the piston will move to the front end of the cylinder moving the flexible rod 26 forwardly through the flexible tube 32 to raise the aerial section 34 which, when extended its full length, picks up the aerial section 35 and moves it upwardly along therewith. By reversing the valve the piston is moved to its original position with the resulting lowering of the aerial sections.

In Fig. 3, I have illustrated a further form of my invention for producing the extension of the aerial sections. A tube 50 is employed having a sweeping curve portion 51 in which a piston 52 may operate. The piston is preferably made up of individual sections comprising buttons 53 against which cup washers 54 abut when maintained in position by shouldered washers 55. A tapered opening 56 is preferably provided in the buttons 53 for the purpose of permitting the two sections of the piston to deflect relative to each other as the piston moves through the sweeping curve portion 51. A sealing element 57 is provided in the shouldered washer 55 for the purpose of sealing the wire 58 therewith. The wire 58 extends through a flexible tube 59 of conventional form and projects into an aperture 61 within the end of the aerial section 34 and is soldered, brazed, or otherwise secured in fixed relation thereto.

The tubular aerial section 62 carries a guiding washer 63 on its end for the purpose of providing stability to the antenna when raised, the length of the upwardly extending portion of the tube 50 being sufficient to have the washer 63 disposed outside of the sweeping curve portion 51 when the antenna is in lowered position. A cap 64 encases the end of the tube through which the

aerial section 62 projects and in which a sealing element 65 is preferably provided. The washer 63 has radial openings 66 through which air or other fluid for producing the piston actuation may pass. A pipe connection 68 is provided on the upper end of the cylinder 50 while a similar connection is mounted on the opposite end thereof through which fluid passes to and from the cylinder ends.

10 When the antenna sections 34 and 62 are in their lowermost position, the piston 52, disposed at the right hand end of the cylinder, is drawn against the flexible tube 59 and the wire 58 is pulled taut through the piston whereupon the 15 clamping collar 70 is secured to the end of the wire to lock the aerial, the piston, the wire and the flexible tube 59 in adjusted unit relation.

This construction produces the raising of both 20 sections of the aerial but is objectionable as the introduction of the helical flexible tube 59 within the aerial section 62 changes the capacity thereof. As noted in dot and dash lines, the curve portion 51 may be less than 90 degrees as illustrated at 25 69 or formed into a U curve as illustrated at 71.

In Fig. 4, I have illustrated a method of raising the aerial sections 34 and 35 without materially 30 effecting the capacity of the antenna while eliminating the use of the flexible di-electric operating element 26. A wire 72 similar to the wire 58 is supported within the length of the cylinder 14 by a plurality of washers 75 which prevent the wire from flexing materially within the tube. The washers are spaced a predetermined distance apart and are joined by one or more flexible 35 cables 76 which are secured to the washers by solder 77 or other means, to the flange 21 of the stem 16 and to the operating end of the cylinder.

In operation the piston 15 moves forwardly and 40 picks up the washers which are moved along therewith as the wire is advanced through the flexible tube 32 to the antenna section 34 which, along with section 35, is raised thereby. Upon reverse movement of the piston the cables 76 pick up the washers and distribute them evenly 45 along the tube to be available to prevent the collapse of the wire 72 when the piston is again moved forwardly. The flexible tube 32 and the casing are shielded beneath the body of the motor vehicle and any changes in capacity which occur 50 from the introduction of the wire within the aerial section 35 which would be slight. A suitable lead-in wire (not herein illustrated) joins the antenna to the radio.

While I have described and illustrated several 55 embodiments of my invention, it will be apparent to those skilled in the art that various changes, omissions, additions and substitutions may be made therein without departing from the spirit and scope of my invention, as set forth in the accompanying claims.

60 What is claimed is:

1. In an extensible aerial, an insulated antenna comprising a plurality of telescoping sections, a cylinder, a piston slidable in said cylinder, and a flexible shaft of dielectric material connecting said piston to said antenna, whereby differential pressures on opposite sides of said piston will move said piston and thereby actuate said antenna.

2. In an extensible aerial for an automobile, a housing adapted to be mounted on the automobile body and insulated therefrom, a rod-like antenna axially slidable in said housing, a pressure cylinder, a piston slidable in said cylinder, a shaft of dielectric material connecting said pis-

ton and antenna, and means for insulating said cylinder from said housing, whereby differential pressures on opposite sides of said piston will move said piston and thereby slide said antenna relative to said housing.

3. In an extensible aerial for an automobile, a housing adapted to be mounted on the automobile body and insulated therefrom, a rod-like antenna axially slidable in said housing, a pressure cylinder, a piston slidable in said cylinder, a flexible shaft of dielectric material connecting said piston and antenna, and means for insulating said cylinder from said housing, whereby differential pressures on opposite sides of said piston will move said piston and thereby slide said antenna relative to said housing.

4. In an extensible aerial for an automobile, a housing adapted to be mounted on the automobile body and insulated therefrom, a rod-like antenna axially slidable in said housing, a pressure cylinder, a piston slidable in said cylinder, a flexible member connecting said piston and antenna, said member being of dielectric material and adapted to transmit forces by tension and compression, and means for insulating said cylinder from said housing, whereby differential pressures on opposite sides of said piston will move said piston and thereby slide said antenna relative to said housing.

5. In an extensible aerial for an automobile, an antenna, a cylinder, a piston slidable in said cylinder, a flexible shaft comprising an inner tension member and an outer compression member surrounding said inner member, said inner member being connected to said piston and said antenna for transmitting tension forces, said outer member abutting said antenna and said piston for transmitting compression forces,

whereby differential pressures on opposite sides of said piston will move said piston and thereby extend and retract said antenna.

6. In an extensible aerial, an antenna, a cylinder having a portion with a curved axis, a piston slidable in said cylinder, said piston comprising two piston sealing members in axially spaced relation to each other, and flexible means for coupling said sealing members so as to permit movement in a curved cylinder while maintaining sealed relation with the side wall thereof, and a flexible shaft connecting said piston to said antenna, whereby differential pressures on opposite sides of said piston will move said piston and thereby actuate said antenna.

7. In an extensible aerial for an automobile, a mounting housing, an antenna movably mounted on said housing, antenna moving power means remotely located with respect to said housing, a flexible housing connecting said mounting housing to said power means, means for insulating said mounting housing from said power means and a dielectric member actuated by said power means and connected to said antenna for extending and retracting said antenna.

8. In an extensible aerial for an automobile, a housing adapted to be mounted on the automobile body and insulated therefrom, an antenna slidably mounted on said housing and comprising an outer tubular section, an inner section telescoping within said outer section, a flexible dielectric actuating member attached to said inner section and adapted to be housed within said outer section when said sections are extended, and an antenna moving power means connected to said actuating member.

WILLIAM EDWARD HANN.
